UNITED STATES PATENT OFFICE.

WILLIAM D. MOORE, OF BIRMINGHAM, ALABAMA, ASSIGNOR TO SAND SPUN PATENTS CORPORATION, OF WILMINGTON, DELAWARE, A CORPORATION OF DELAWARE.

CENTRIFUGAL PIPE HEAD CORE.

Application filed January 29, 1926. Serial No. 84,580.

This invention is an improvement in centrifugal casting in sand molds, and more particularly in head cores for such molds.

In casting centrifugally in tiltable molds 5 in the manner shown and described in my Patent Number 1,471,052, dated Oct. 16, 1923, the charge is poured into the spigot end of the mold while the mold is inclined, the charge running by gravity toward the 10 bell end.

Because of the inclination of the mold during charging, the end toward which the metal flows is usually closed by a head core, which provides an abutment to prevent over 15 flow of the charge, and assists in shaping the bell end of the casting.

Even with the most careful manipulation of the mold, to meet the charge, as specified in application No. 42,168, filed July 8, 1925, 20 a part of the charge is liable to strike the face of the head core, and rapidly cooling, such portion adheres to the head core forming a thin film over a part or all of the face.

In the preferred method, the mold is rotated at a relatively low speed during the 25 charging, and at a relatively high speed during the casting, and the change from the low to the high speed is abrupt. During the first stage, that is the charging, the 30 speed of rotation is not sufficient to hold the metal on the mold wall by centrifugal force, and the molten metal lies longitudinally thereof, substantially in a mass, so held by gravity.

The charging operation takes place while the mold is inclined, and is preferably finished co-incident with the complete restoration of the mold to the horizontal or level position.

40 When the mold is spun, that is when the relatively rapid rotation commences, or while it is proceeding, the film of partly cooled metal on the head core is thrown off, and in the usual arrangement of head cores, it travels radially to the casting wall. The cooling of this film has advanced far enough, so that the film is not absorbed into the wall of the casting, but forms a roughness thereon, which later must be ground 45 away.

One of the primary objects of the present invention is the provision of a head

core of a formation such that the film of partially cooled metal will be retained on the head core. 55

The material from which the head cores are made is relatively expensive, because of the oil used therein, and another object of the invention is the provision of a core of a formation such that a minimum amount 60 of sand and oil is required to make the same.

With these and other objects in view the invention consists in the construction and novel combination of parts fully described hereinafter, illustrated in the accompanying 65 drawings, and pointed out in the claims appended hereto, it being understood that various changes in the form, proportion, size and minor details of construction within the scope of the claims, may be resorted to 70 without departing from the spirit of the invention.

In the drawings forming a part hereof; Fig. 1 is a side view with parts in section of a part of the apparatus for casting 75 centrifugally in tilting molds, by the method of the patent above mentioned.

Fig. 2 is a longitudinal section through that end of the mold provided with the head core and through the improved head core. 80

Fig. 3 is a sectional view showing a modified form of core plate.

The embodiment of the invention shown in the drawings, is shown in connection with a sand lined mold, including a flask composed of a body 1 and a lining or mold 2 of sand within the flask. The mold is supported on a tilting carriage 3 pivoted at 4 to swing into inclined or horizontal position, and the carriage is moved into tilted position by fluid pressure apparatus indicated generally at 5. The weight of the carriage and associated parts is relied upon to return the mold to level or horizontal position, and the mold is rotated by means of a motor indicated at 6, which is mounted on the carriage, and has the motor shaft thereof releasably connected to the flask. 85 90 95

A bell shaped extension 7 is connected with one end of the flask, and the said extension has a marginal flange 8, to which is connected the flange 9 of a sleeve 10, by means of key-pins 11. The head core 12 is of any usual or desired conformation, and 100

it is placed within the bell shaped extension 7 of the flask, being held by the sleeve 10. The external contour of that portion of the flange which extends inwardly beyond the sleeve 10 corresponds to the desired internal contour of the bell end of the casting 13, and referring to Fig. 2 it will be noticed that the bore of the sleeve 10 at the flange is tapering.

10 The core is composed of sand and an oil, such as linseed oil, the parts being mixed in suitable proportions, until every particle of the sand is coated with the oil. The sand is then shaped to form the core which is afterwards dried by heat to volatilize the oil. Because the head core is at the end toward which the molten metal is charged, it is desirable that it completely close the said end, and since it is the core for the bell end 20 of the mold, it must be relatively long. Thus a relatively large amount of oil is required for each head core.

The core is reinforced and supported at the end which engages the sleeve 10, the said 25 sleeve constituting the support for the core, by means of an internally flanged ring 14, whose peripheral surface fits the tapered portion of the sleeve, and the core is held from outward movement by means of wedges 30 15, which are passed through radial openings in the sleeve, and against the inner ends of which the flange of the ring 14 bears.

In head cores as heretofore constructed, the inner end thereof is of a conformation 35 such that any molten metal freezing thereon during the charging, and slow rotation of the mold, will be flung off during the casting stage, or rapid rotation of the mold, onto the inner surface of the casting, there to form 40 a roughness which later must be ground away. In the present invention the inner end of the mold is so shaped that such adhering metal will be retained during the casting or rapid rotation.

45 To insure this end, the inner end of the core is deeply recessed as shown at 16, the recess extending axially and having its side wall of a conformation such that it will oppose radial movement of metal within the 50 cavity or recess under the influence of gravity. That is at least a portion of the wall at the open end of the cavity should be cylindrical or undercut to resist radial movement of the metal. The retention of the 55 metal is also facilitated by the depth of the cavity and the cost of the core is decreased by lessening the amount of sand and oil used.

It will be evident that any congealed iron 60 or metal which may temporarily adhere to the face of the head core is trapped, to prevent it from applying itself to or becoming incorporated with the casting wall.

While the method of preventing trapped metal from reaching the core wall is exemplified in a head core for castings with bell

ends, it is obvious that it is equally applicable to castings with plain ends, or in any case where it is necessary to produce a casting free from the troubles which are avoided by the use of the improved core. It is equally obvious that the use is not limited to cores of oil and sand.

In Fig. 3 a core is shown with an alternate form of core plate. In this construction the core 17 is supported by a plate 18, of 75 tapering form externally like the plate 14. Instead however of being a ring only, the plate has a transverse partition 19. The partition is provided at the face adjacent the casting with an annular groove 20. The side walls are undercut as shown, which provides for a dove tailed effect or connection between the core proper and the core plate. When dry this connection provides a perfect union until the casting operation is completed. The arrangement also enables the making of a very deep recess 21, the said recess extending almost to the core plate partition, and to the end of the casting.

I claim:

1. A core for that end of a centrifugally operated mold toward which the metal flows in charging, having at its inner end or face an axial recess extending part way through the core.

2. A core for that end of a centrifugally operated mold toward which the metal flows in charging, having at its inner end or face an axial recess extending part way through the core, the side wall of the recess shaped at the open end to oppose radial movement of metal within the cavity by centrifugal action.

3. A head core for the end of a centrifugally operated mold toward which the metal is charged having the inner end or face thereof shaped to receive and retain excess metal thrown thereon during charging against radial movement by centrifugal action.

4. A head core for closing the end of a centrifugally operated mold toward which the metal is charged, said core having an axial recess the wall at the open end thereof shaped to oppose radial movement of metal within the cavity by centrifugal action.

5. A head core for closing the bell end of a centrifugally operated mold shaped to produce a casting with a bell end, the inner end of the core having means to receive and retain excess metal thrown thereon during charging against displacement by centrifugal action.

6. A head core for closing the bell end of a centrifugally operated mold shaped to produce a casting with a bell end, the core shaped to serve as a core for the bell and to close the end, the inner end of the core having means to receive and retain excess metal thrown thereon during charging

against displacement by centrifugal action during casting, said means including an axial recess in the core, the side wall of the recess at the open end thereof substantially cylindrical.

7. The step in the method of centrifugally casting hollow bodies with bell ends in tilting molds, which consists in trapping any congealed metal which may adhere to the head core in charging and retaining said metal during casting to prevent contact thereof with the casting wall.

8. A machine for centrifugally casting hollow bodies, including a tilting refractory lined mold, means to tilt the mold, and a head core of refractory material closing the lower end of the mold deeply recessed axially for the purpose set forth.

9. A machine for centrifugally casting hollow bodies, including a tilting refractory lined mold, means to tilt the mold, and a head core of refractory material closing the lower end of the mold deeply recessed axially for the purpose set forth, said recess formed to oppose movement of trapped metal toward the mold wall.

10. A machine for centrifugally casting hollow bodies, including a tilting refractory lined mold, means to tilt the mold, and a head core of refractory material closing the lower end of the mold deeply recessed for the purpose set forth, the recess formed to

trap and retain congealed metal gaining access thereto.

11. A core for closing one end of a centrifugally operated mold having at the inner end thereof an axial recess extending part way through the core.

12. A core for the end of a centrifugally operated mold including a core plate and a refractory core body, the plate having an annular groove with undercut side walls, and the core body a similarly shaped rib fitting within the groove.

13. A core adapted for use in centrifugal casting, including a plate having at one face an annular groove with undercut side walls, and a body of refractory material having a rib fitting within the groove, the end of the body remote from the plate having a relatively deep axial recess.

14. A core adapted for use in centrifugal casting, including a plate having at one face an annular groove with undercut side walls, and a body of refractory material having a rib fitting within the groove.

15. A core adapted for use in centrifugal casting, including a rigid plate and a body of refractory material, said plate and body having a dove tailed connection.

Signed at Birmingham, in the county of Jefferson and State of Alabama, this 15th day of January A. D. 1926.

WILLIAM D. MOORE.
